UNITED STATES PATENT OFFICE

121,087

DESIGN FOR A FOUNTAIN PEN OR SIMILAR ARTICLE

Anatol N. Andrews, Los Angeles, Calif.

Application December 4, 1939, Serial No. 88,681

Term of patent 14 years

To all whom it may concern:

Be it known that I, Anatol N. Andrews, a citizen of the United States, residing at 1435 West 25th Street, city of Los Angeles, in the county of Los Angeles and State of California, have invented a new, original, and ornamental Design for a Fountain Pen or Similar Article, of which the following is a specification, reference being had to the accompanying drawing, forming part thereof.

Figure 1 is a side elevational view of a fountain pen or similar article in a closed position showing my new design;

Fig. 2 is an elevational view of the opposite side of Fig. 1 and showing a pen clip which is of substantially the same configuration as the entire fountain pen, except that it is on a greatly reduced scale.

I claim:

The ornamental design for a fountain pen or similar article, as shown and described.

ANATOL N. ANDREWS.
